UNITED STATES PATENT OFFICE.

EARNEST RICHARD MARTIN, OF RIDGEFIELD PARK, NEW JERSEY.

RECEPTACLE CAP.

Application filed May 17, 1921. Serial No. 470,409.

To all whom it may concern:

Be it known that I, EARNEST R. MARTIN, a citizen of the United States, and resident of Ridgefield Park, in the county of Bergen and State of New Jersey, have invented a new and Improved Receptacle Cap, of which the following is a full, clear, and exact description.

My invention relates to a receptacle cap and more particularly a dispensing cap for a fluid within the receptacle.

In connection with the filling of receptacles such as storage battery cells in which fluid must be poured, to a predetermined depth, it is a well appreciated fact that considerable difficulty has been experienced incident to the fact that insufficient fluid or an excess of the same has often been introduced into the receptacle.

This difficulty is true in various types of receptacles such as ink wells, etc., but the greatest objection has been experienced in connection with battery cells, it being understood that an excess of distilled water introduced into these cells will cause an inefficient operation of the same, while too small an amount of fluid will primarily permit the solution within the cell to include too great an acid agent, as well as increasing the danger of the plates becoming exposed due to the evaporation of the water in the solution, while the battery is charging.

Thus my present invention has reference to a receptacle cap suitable for association with any desired type of container and by means of which primarily an operator may introduce just that amount of fluid with which a receiving receptacle should be filled.

Thus a further object of my invention is the construction of a device of the character specified which will not necessitate the utilization of a stopper or extraneous member for preventing an evaporation of the fluid while the receptacle with which it is associated is not in use.

Still another object of this invention is the construction of a cap for receptacles by means of which the receptacle may be inverted prior to the introduction of the inner end of the same into the receptacle to be filled without any danger of the fluid contained within said receptacle escaping.

Still another object of this invention is the provision of a cap which shall be ex-

tremely simple in construction and which may be manufactured at a minimum figure.

Reference is had to the attached sheet of drawings as illustrating practical embodiments of my invention, and in these drawings it will be seen that—

Figure 1 is a sectional side view of a receptacle having one form of my cap applied thereto and showing the same associated with a conventional battery wall.

Figure 2 is an end view of the cap as illustrated in Figure 1.

Figure 3 illustrates the said cap while in the act of filling a receptacle.

Figure 4 shows a slightly different form of cap than that illustrated in the preceding figures.

Figure 5 is an end view of this latter type of cap, and

Figure 6 shows the same while in use and associated with a receptacle of the type illustrated in Figure 1.

Referring now more particularly to Figure 1 it will be seen in the embodiment illustrated that the reference numeral 10 indicates the receptacle to be filled, in this instance a battery jar having plates 11 positioned within it. The said jar is provided in the usual manner with an extension and filling opening 12 by means of which the fluid contained within the receptacle 13 may be poured into the jar 10, the flow of fluid being regulated by means of my improved type of cap.

As has been shown in Figure 2, as well as in the figure mentioned, the said cap includes a body portion 14 adapted to firmly embrace the outer end of the receptacle 13, an end wall 15 being provided, which end wall closes the outer end of the cap, with the exception of an opening 16 conforming roughly to a double key-hole opening for a purpose hereinafter more fully specified.

Furthermore a pair of lugs 17 are secured to the end wall 15 and extend outwardly therefrom to any distance which may be desired. Thus assuming that a battery jar is to have its fluid replenished, the lugs are made substantially equal in length to the depth of fluid which is to exist upon the plates 11, the dangers of not reaching or exceeding this depth being well understood in the art.

It will be found that by virtue of the peculiar construction of the opening 16 that the receptacle 13 may be inverted freely and

held vertically without any fluid passing through the opening 16. Thus an operator may place the receptacle 13 in the position shown in Figure 1 the lugs 17 thereof contacting with the upper edges of the plates 11. Further upon the receptacle being tilted as has been shown in Figure 3 it will be found that fluid will flow freely from the opening 16, and by virtue of the lugs 17 it will not be necessary for the operator to use any care in the introduction of this fluid other than placing the lugs in contact with the upper edges of the plate. The flow of fluid will continue until the same has reached the height shown in Figure 1, and upon this occurring it will be obvious that a water seal will be formed which will preclude any danger of the fluid exceeding a predetermined depth.

In Figure 3 the same type of cap as has been described before, is illustrated in connection with a different type of receptacle, such as an ink well 18, and as aforesaid, indicates the position in which the receptacle 13 must be placed to exert a pouring of the fluid within the receptacle 13.

In some instances a certain amount of air might leak between the body 14 of the cap and the receptacle 13, and it will be found after this occurred that the fluid within said receptacle would escape irrespective of the fact that the same were held in a vertical inverted position.

With this in mind I have devised a slightly different form of cap which may be utilized to advantage where danger of this occurrence exists, and reference is had to Figures 4 to 6 as illustrating this cap.

This latter cap includes a body portion 19 associated in any desirable manner with the receptacle 13, the said cap being formed with an end wall 20 providing an opening 21 similar. However it will be noted that an enclosed body 22 is provided in this type of cap in lieu of the lug 17, and this body terminates in an end wall 23 formed with an opening 23' corresponding to the opening 16.

This type of cap acts in the same manner as that aforesaid with the exception that when the same is held in a vertical inverted position the valve 25 co-operates with the seat 24 and prevents the escape of any fluid from the body 22, which fluid might flow through the opening 21. Thus the es-

cape of fluid is doubly prevented, but as has been indicated in dotted lines in Figure 6 the flow may be started by inclining the cap and receptacle with which it is associated. Upon this occurring the valve 25 will move from its shallow seat 24, as has been shown in dotted lines to a point adjacent the wall 23 and body 22. The fluid will now flow to the depth desired, but upon the same being returned to its vertical position the valve 25 will again close the opening of the wall 23 and the flow will cease.

Thus it will be seen that I have provided a cap by means of which all of the objects set forth in the preamble of this specification may be accomplished, and it will be understood that numerous modifications of structure might readily be resorted to without in the least departing from the spirit of my invention, which I claim as;

1. A receptacle cap including a body portion, an end wall for said body portion, said end wall being formed with an elongated opening including longitudinal sub-divisions of different widths. 80

2. A receptacle cap including a body portion and means forming a part of said body portion for preventing the flow of fluid through said cap when the same is in a vertically inverted position, said means permitting of a flow of fluid through an opening formed in said cap upon said cap being inclined beyond the vertical. 85

3. A receptacle cap including a body portion, an end wall for said body portion, said end wall being formed with an elongated opening, and means secured to said cap for permitting of the flow of fluid through said opening into a receptacle to only a predetermined depth. 90

4. A receptacle cap including a body portion, an end wall for said body portion, said end wall being formed with an opening, the edge of said opening defining substantially a circle and a slot of less width than the circle merging therewith and lugs secured to and extending beyond said end wall. 100

5. A receptacle cap including a body portion, an end wall for said body portion, said end wall being formed with an opening, the edge of said opening defining a substantially cruciform figure and means connected to said end wall and extending beyond said opening. 105

EARNEST RICHARD MARTIN.
